[57] CLAIM

The ornamental design for a handle for pliers or similar article, as shown and described.

DESCRIPTION

FIG. 1 is a top left side and front perspective view of a handle for pliers or similar article, showing my new design;

FIG. 2 is a bottom right side and rear perspective view thereof;

FIG. 3 is a top plan view thereof;

FIG. 4 is a bottom plan view thereof; and,

FIG. 5 is a left side elevational view, the right side being the mirror image thereof.
